MINIATURE GOLF APPARATUS AND GAME

Thomas D. O'Herron, 70 Liberty St., Dansville, N.Y.

Filed May 22, 1959, Ser. No. 815,189

6 Claims. (Cl. 273—176)

The present invention relates to a miniature golf apparatus and game to be set up on a lawn or green out of doors, or on an indoor floor, if desired, and particularly adaptable to be used by novices in the game of golf.

An object of the invention is to provide a new and improved miniature golf apparatus having a number of assemblies each of which represents a "hole" and which can be arranged in a selected pattern for a miniature golf course.

Another object is the provision of a miniature golf apparatus composing a barrier having a tunnel through which the ball may pass and a deflector arranged behind the tunnel for deflecting the ball to either side.

Yet another object is to provide a new and improved miniature golf apparatus of the foregoing kind having rubber barriers so that the ball bounces back if not hit in the correct direction.

A further object is the provision of a miniature golf game composed of a plurality of standard barrier and deflector units through which a ball must pass, the units being adapted to be placed on a lawn or green in a selected pattern and being easily removable to another position or for storage, and each unit or assembly being subject to some individual variation of shape or spacing when installed, so that there may be some individual variations in the separate "holes" of the game.

It is seen from the foregoing disclosure that the above mentioned objects of the invention are well fulfilled. It is to be understood that the foregoing disclosure is given by way of illustrative example only, rather than by way of limitation, and that without departing from the invention, the details may be varied within the scope of the appended claims.

Fig. 1 is a perspective view of the miniature golf apparatus parts constituting one individual "hole" assembly, comprising separate barrier and deflector units arranged in a preferred manner;

Fig. 2 is a top view of the deflector unit;

Fig. 3 is a top view of the barrier unit;

Fig. 4 is a front elevational view of the barrier unit; and

Figs. 5, 6, and 7 are cross-sectional views of the unit shown in Fig. 4 taken on the lines 5—5, 6—6, and 7—7 thereof.

The same reference numerals throughout the several views indicate the same parts.

Referring now to the drawings, in Fig. 1 is illustrated the miniature golf apparatus according to the invention, comprising a barrier unit, indicated generally at 11, and a deflector unit, indicated generally at 13, placed to the rear of the barrier unit and spaced therefrom a short distance in the preferred arrangement. The barrier unit includes an upstanding elongated generally rectangular block 15 made of a suitable resilient material and having preferably a substantially flat front face 17. A tunnel 19 extends through the central lower portion of the barrier block 15 to provide a passageway through which a ball may be hit. A ball hit toward the tunnel

2

19 but which is aimed slightly inaccurately bounces off the front face 17 of the rubber block, whereafter the player has another try to get the ball through the tunnel.

Preferably, the block 15 is provided with rearwardly angled wing ends 21 and 23 at either side of the block 15 to provide additional deflecting surfaces for a ball. The block 15 and the two wing ends 21 and 23 are desirably mounted on a rigid backing and mounting plate 25 preferably made of plastic or other like material. Although the block 15 and the ends 21 and 23 may be cemented to the backing plate 25, in the preferred embodiment they are pinned in place by a plurality of pins 27 extending through these components into the backing plate in a manner to be explained. A flag 29 is desirably provided and is suitably mounted on the plate 25 for indicating the number of the hole which the particular barrier and deflector unit is intended to represent.

The deflector unit 13 is arranged centrally behind and spaced from the barrier unit 11 to deflect a ball hit through the tunnel 19 to either side. The deflector unit comprises two rearwardly and outwardly curved deflecting plates 31 and 33 joined together at their front ends so that the plates are oppositely disposed about an imaginary center line between them. A ball coming through the tunnel strikes a portion of either of the deflector plates 31 or 33 to be deflected sidewardly.

To provide an additional barrier in going through the tunnel 19 successfully, the adjoining front ends of the deflector plates 31 and 33 have mounted thereon a resilient bumper 35. A ball passing through the tunnel 19 has the additional chance of striking the bumper 35 and being deflected back out through the tunnel 19 or partially in that direction.

The apparatus shown in Fig. 1 provides one of the "holes" for a miniature golf course. A number of the setups may be disposed in any desired pattern around a lawn or green, nine holes or eighteen holes being provided in the most usual game. To secure the barrier unit 11 in place on a lawn or the like, a plurality of ground spikes 37 extend through lugs in the backing plate 25 in a manner to be further explained. Preferably two spikes 37 are provided each having a laterally enlarged head which extends over the top edge of the backing plate 25. In a similar manner, the deflector unit 13 is secured in place on the lawn or the like by other similar spikes 41. Preferably two spikes 41 are provided for each deflector plate each having an enlarged head which fits over the top edge of the plate. The deflector unit 13 is shown to an enlarged scale in Fig. 2. The deflector plates 31 and 33 in the preferred form are each slightly more than 90 degree arcs of a circle, the extreme front ends in excess of an exact quarter circle being flattened toward each other or straightened out so as to lie flat one against the other, these straight portions being cemented or otherwise suitably secured together. The plates 31 and 33 are preferably made of plastic, or some similar material which will bounce off a golf ball or rubber ball impinging upon them. The material forming the plates 31 and 33 should also be relatively resistant to deterioration by water, since it is contemplated that the golf apparatus may be left out of doors and be exposed to the elements. Of course, the deflector plates may be more or less than 90 degree arcs, according to the type of deflecting surface required, and they may be made as other kinds of rearwardly and outwardly slanting curved surfaces other than arcs of circles. A successful model has been made in which the plates 31 and 33 are arcs of a nine inch radius, but this dimension is not to be taken as limiting.

Turning now to the barrier unit 11, as shown in Figs. 3 and 7, the plate 25 is likewise preferably made of plastic sheeting. The backing plate 25 at either end, see Fig.

3, is angled outwardly and backwardly at about 45 degrees to provide a mounting for the wing ends 21 and 23. The angled end portions 25 are preferably integral with the central portion of the backing plate. As with the deflector plates, any suitable, rigid material other than plastic may be used which is resistant to deterioration by the weather. The central block 15 is preferably integral with the two wing ends 21 and 23, the entire rubber barrier block being molded as a single unit for the sake of convenience of manufacture.

The tunnel 19 is an inverted U-shaped member having a pair of spaced upstanding flanges 43 and 45 rising from its outer surface toward one end. The flanges 43 and 45 provides a groove or slot extending around the tunnel member 19. The backing plate 25 has a corresponding inverted U-shaped recess, the edges providing the recess fitting tightly into the groove formed by the flanges 43 and 45. The central rubber block 15 likewise has a corresponding U-shaped recess which fits over the forward portion of the tunnel 19 and the forward flange 45.

As seen in Fig. 5, the rear surface of the backing plate 25 approximately centrally of the rear flange 43 has a plurality of attached rearwardly extending lugs 47 which are apertured for receiving the shaft of the flag 29. The lugs 47 are vertically spaced, of course, two lugs being here shown, and the end of the shaft of the flag 29 extending through them rests on the top edge of the flange 43. The flag 29, as has been mentioned, is imprinted with a number representing the hole number, the numbers running from 1 upwards consecutively to any desired number of holes, 18 holes being the normal maximum.

Referring now especially to Fig. 6, the back surface of the backing plate 25 is provided with a plurality of vertically aligned and spaced rearwardly directed lugs 49 each provided with an aperture for receiving the spikes 37. The spikes 37 each have a tapered shank the end of which extends into the ground. The heads of the spikes are enlarged laterally in one direction so as to extend over the top edge of the backing plate 25. Thus, with the spikes projecting through the apertures in the lugs 49 into the ground, the heads of the spikes bear down the top edge of the backing plate 25 to hold the barrier unit securely in place at a selected location. Although not shown in the drawing, the deflector plates 31 and 33 are provided with similar lugs through which the spikes 41 extend.

Although the central rubber block 15 and the wing ends 21 and 23 may be cemented to the backing plate 25, in the preferred embodiment this securing is obtained by the means of the pins 27 as illustrated in Fig. 7. The pins 27 each have a tapered shank and an enlarged head. Aligned apertures are provided in the backing plate and the rubber barrier block. Thus, the rubber barrier is provided with a series of vertically and laterally spaced approximately horizontally disposed bores 51, and aligned tapered apertures 53 are likewise provided in the backing plate 25, the tapered shank of the pins 27 each extending through one of the bores to be force-fitted into the corresponding aperture 53. The pins 27 are distributed in a desired pattern on either side of the tunnel 19 in order to provide an adequate holding means for the entire rubber barrier.

It has been mentioned that in a successful model, the deflector plates are arcs of a nine inch radius. For this size of deflecting unit, good results are obtained when the tunnel 19 is about 4½ inches in width, the height of the tunnel being sufficient to pass a regulation size golf ball or a rubber ball of about the same size. The barrier unit 11 is preferably about the same width as the deflector unit, that is, about 18 inches from one extreme end to the other. The height of the units may conveniently be about four inches.

In the use of the miniature golf apparatus according to the present invention, a barrier unit 11 and a deflector unit 13 are provided for each hole, and although

single units may be used for practice purposes, in use it is expected that 9 or 18 holes will be set up on a lawn or a green. The barrier units 11 are located at selected positions and secured in place by inserting the spikes 37 through the lugs 49 and pounding them into the ground. A deflector unit 13 is located behind an imaginary center line through the tunnel 19 and spaced from the tunnel 19 in the manner shown in Fig. 1 and is similarly secured to the ground. The relative location of the different miniature golf apparatus, each representing a hole, is selected by the user and depends on the amount of available space, among other things. The distance of each deflector unit behind its barrier unit may also be varied to allow some flexibility in the game.

A regulation golf ball or a rubber ball about the same size is used, together with a regulation size golf club. A number 1 to 5 club or a putter is recommended. For children, children's clubs may be used.

In the use of the miniature golf apparatus, the ball is aimed toward the tunnel 19. If it misses the tunnel 19, it may strike the face 17 of the rubber barrier block and be deflected. In the case that the ball passes through the tunnel 19, it may also strike the rubber bumper 35 on the deflector unit 13, and bounce back into the tunnel or in the direction of the tunnel. If the ball passes to either side of the bumper 35, it strikes one of the deflector plates 31 or 33 and is deflected to the side, whereupon the ball may be hit toward the next miniature golf apparatus representing the next hole.

A set of rules may be made up for a miniature golf game using the apparatus of the present invention. For instance, it may be required to play the complete course without touching the ball, and if the ball is touched by hand except at the starting, this may count two strokes. If the ball becomes trapped in the tunnel, it may be moved on through and count two strokes. The strokes for each hole may be counted and scored, and may be compared to a par. It is recommended that a par of three strokes for short holes be adopted, or else one stroke for every 15 to 20 feet of course. Rules similar to these or any other rules which the particular players may prefer may be adopted.

One or more of the miniature golf apparatus may be used indoors. In this case, the spikes 37 and 41 are not used. If it is found to be necessary, the various barriers and deflector units may be weighted by small weights or the like to prevent their being moved by the impact of a ball striking against them.

The miniature golf apparatus of the present invention is relatively inexpensive to manufacture, and is simple to set up and use by a relatively unskilled player. The units are designed to be resistant to weather so that they may be left on the lawn or green. Sufficient flexibility in the placement of the various miniature golf apparatus is allowed to adapt the game to be played in areas of widely different sizes.

It is seen from the foregoing disclosure that the above mentioned objects of the invention are well fulfilled. It is to be understood that the foregoing disclosure is given by way of illustrative example only, rather than by way of limitation, and that without departing from the invention, the details may be varied within the scope of the appended claims.

What is claimed is:

1. A miniature golf apparatus including a barrier unit and a deflector unit, said barrier unit comprising an upstanding elongated resilient block having a tunnel extending through the central lower portion thereof, said deflector unit comprising a pair of oppositely disposed rearwardly and outwardly curved deflector plates secured together at their front ends, said deflector unit being arranged behind said tunnel so that a ball hit through said tunnel is deflected to either side by said deflector plates, the ball being deflected by said resilient block when it strikes said barrier unit to either side of said tunnel.
2. A construction as defined in claim 1, further in-

cluding a resilient bumper attached to the adjoining front ends of said deflector plates to deflect a ball impinging thereon back in the direction of said tunnel.

3. A construction as defined in claim 1, wherein said miniature golf apparatus is adapted to be fastened to the ground, apertured lugs on each of said units, and a plurality of spikes each extending through at least one of said lugs into the ground, said spikes each having an enlarged head overlying a portion of one of said units.

4. A miniature golf apparatus including a barrier unit and a deflector unit, said barrier unit comprising an upstanding elongated rubber block, a rigid backing and mounting plate, means for attaching said rubber block to said backing plate, and a tunnel member extending through said rubber block and mounting plate, said deflector unit comprising two oppositely disposed rearwardly and outwardly curving arcuate deflector plates attached to one another at their front ends, and a rubber bumper secured to the front ends of said deflector plates, said deflector unit being arranged centrally behind said tunnel member so that a ball hit through said tunnel member is deflected to either side by said deflector plates and is deflected back in the direction of said tunnel member upon striking said bumper.

5. A construction as defined in claim 4, wherein said tunnel member has a pair of upstanding spaced flanges

defining a slot therebetween, said backing plate having a correspondingly shaped recess received in said slot.

6. A miniature golf game comprising a plurality of miniature golf apparatus each including a barrier unit and a deflector unit, each said apparatus representing a "hole" and adapted to be disposed about a lawn or the like to provide a course, each said barrier unit comprising an elongated upstanding resilient block having a tunnel therethrough to allow passage of a ball, and each said deflector unit comprising a pair of oppositely disposed rearwardly and outwardly curving deflector plates attached to one another at their adjoining front ends, a resilient bumper secured to the adjoining front ends of said deflector plates, said deflector unit being arranged substantially centrally and spaced rearwardly of said tunnel in its respective barrier unit, so that a ball hit through said tunnel may be deflected sidewardly by said deflector plates and may be deflected back in the direction of said tunnel when impinging on said bumper, means for releasably securing said units to the lawn or the like.
